E. J. MOYNIHAN.
ROCK CARRYING STEAM SHOVEL DIPPER.
APPLICATION FILED JUNE 26, 1917.

1,263,791.

Patented Apr. 23, 1918.

FIG. 1

UNITED STATES PATENT OFFICE.

EUGENE J. MOYNIHAN, OF SAN FRANCISCO, CALIFORNIA.

ROCK-CARRYING STEAM-SHOVEL DIPPER.

1,263,791.

Specification of Letters Patent. Patented Apr. 23, 1918.

Original application filed April 12, 1917, Serial No. 161,641. Divided and this application filed June 26, 1917. Serial No. 176,970.

To all whom it may concern:

Be it known that I, EUGENE J. MOYNIHAN, a citizen of the United States, residing at San Francisco, in the county of San Francisco and State of California, have invented new and useful Improvements in Rock-Carrying Steam-Shovel Dippers, of which the following is a specification.

The present invention relates to improvements in the dippers of steam shovels, dredgers, and the like, the present application being a division of an application filed by me April 12, 1917, Ser. No. 161,641. The object of the invention is to provide a dipper which can be used either as a dipper of ordinary form or as one which, without any material increase in size will unload a rock which is so large that it can not be unloaded by the ordinary dipper unless it can be rolled.

In the accompanying drawing, Figure 1 is a side view of my improved dipper; Fig. 2 is a plan view thereof; Fig. 3 is a detail perspective view of a part thereof, removed 25 from the dipper; Fig. 4 is a side view of the dipper converted into a dipper of form suitable for handling large rocks.

Referring to the drawing, 1 indicates a dipper having a front portion 2 of the usual form, its upper part having the usual cutting teeth 3, which, however, form no part of the present invention. The front portion 2 is formed integral with side pieces 4, which are secured on the outer sides of a yoke-shaped piece 6, from which extend rearwardly eyes 7, through which extends a pintle 8, said pintle also extending through eyes 9, formed on a plate 10, secured to the under side of a dipper handle 11 at its outer 40 end.

From the central portion of the piece 6 extends upwardly a casting 12 having an eye or bearing for a pivot pin 13 by which is pivoted the usual bail 14.

To the outer sides of said side pieces 4 are secured, by rivets 16, cheek plates 17, the rear portions 18, of which extend inwardly behind the back or central portion of the yoke-shaped piece 6, as far as the eyes 7 and then rearwardly and upwardly in parallel planes, their upper ends being connected with the upper ends of back braces 19, the lower ends of which are connected to a bolt 21 extending transversely through the usual

casting 22 secured on the top of the dipper 55 handle 11.

The front 2 of the dipper is extended downward to about the same depth as the front of the ordinary dipper, but the dipper handle is connected much nearer to the top 60 than in the old construction, since it is pivotally secured to the lower portion of the back of the dipper, which is much shorter than that of the ordinary dipper.

There is attached to the sides and back of 65 the dipper, which form the upper section of the dipper, a lower section 23 comprising a front yoke-shaped piece 24 and a rear yoke-shaped piece 26, riveted as shown at 27, together and to sides 28, the piece 26 having 70 formed thereon lugs 29 for use with a door 30, and having secured thereto a back piece 31. Said pieces 28, extend upwardly above said pieces 24, and are secured by bolts 32 to the lower portions of the cheek plates 17, 75 and the upper end of the back piece 31 is likewise screwed to the back of the upper section. To the lugs 29 are hinged arms 33, carrying the door 30, which is also secured by a latch to the front of the dipper. 80

If the lower section 23 be removed, there can be substituted therefor a support 34, attached to front ends of arms 36, which extend in large curves and are pivoted, as shown at 37, at their rear ends to the upward extensions 18 of the cheek plates 17, in the same manner as the arms of the door of the dipper of the usual form, but it is not now a door in the proper sense of the word, since it does not close the opening in the 90 bottom of the dipper, but serves to support a large rock between itself and the dipper proper. A narrow strip 38 is removably attached to the arms 36 at the rear of the support 34 and forms a support section which 95 is removed when it is desired to enlarge the opening between the dipper body and the arms 36.

The arms 33 and 36 are provided with racks 39, which are engaged by pawls 41 on 100 a shaft 42 extending in bearings at the under side of the dipper handle. To the bottom of the support 34 are secured bearings 43 for a latch 44 which can enter a hole 46 in a metal plate 47 which extends on the 105 front and rear sides of the lower end of the front of the dipper. This plate 47 not only supports the front edge of the door, or of

the support 34, but reduces the wear on the front of the dipper, being changed as often as necessary. To the rear end of the latch is connected one end of a chain 48 the other end of which is connected with a lever 49 pivoted on the under side of the dipper handle and the outer end of which is connected to a chain 51 leading to a point suitable for operation for withdrawing said latch from engagement with the front of the dipper. To said lever is attached one end of a chain 52, the other end of which is attached to one of said pawls 41.

10. The support 34 is withdrawn by the cable 53, the use of which is more particularly described in United States Letters Patent No. 1,210,194, Dec. 26, 1916.

I claim:

15. 1. A dipper having a back in upper and lower sections, the lower section being removable from the dipper without removing any part of the front of the dipper or chang-

ing the connection of the dipper with the dipper handle.

2. A dipper having a back and sides each 25 in upper and lower sections, each lower section being removable from the dipper without removing any part of the front of the dipper or changing the connection of the dipper with the dipper handle.

3. A dipper having a back in upper and lower sections and a front in a single piece, the lower section being removable from the dipper without removing any part of the front of the dipper or changing the connection of the dipper with the dipper handle.

35. 4. A dipper having a back and sides each in upper and lower sections and a front in a single piece, each lower section being removable from the dipper without removing any part of the front of the dipper or changing the connection of the dipper with the dipper handle.

40. E. J. MOYNIHAN.
